UNITED STATES PATENT OFFICE.

EDWARD S. ABRAHAMS, OF INDIANAPOLIS, INDIANA.

ILLUMINATOR FOR SPEEDOMETERS AND GAGES.

1,212,306.

Specification of Letters Patent. Patented Jan. 16, 1917.

Application filed June 19, 1914, Serial No. 848,144. Renewed July 6, 1916. Serial No. 107,870.

To all whom it may concern:

Be it known that I, EDWARD S. ABRAHAMS, a citizen of the United States, residing at Indianapolis, in the county of Marion and State of Indiana, have invented new and useful Improvements in Illuminators for Speedometers and Gages, of which the following is a specification.

This invention relates to means for illuminating the indicators of speedometers or gages, and a device of such character made to accord with my invention comprises a casing that has a transparent front, an opaque dial with apertures therethrough which are located in front of indicating cylinders or number-wheels, an opaque disk with apertures for the passage of the cylinders or number-wheels; the dial and disk being maintained by the casing in parallel relation one to the other and separated to form a light chamber, the disk having a bowl shaped depression to receive an incandescent lamp for illuminating the characters on the cylinders or number-wheels.

The invention also comprises a structure that is made so that the lamp, its socket and connecting piece may be readily attached and detached without disturbing the registering mechanism contained therein.

The object of my invention is to provide a gage, as an odometer or speedometer with a lamp that is incased within the frame of such measuring device, the lamp being to one side or behind an opaque dial which will obscure the lamp, the light rays from the lamp illuminating the exposed portion of the cylinder or number-wheel.

A further object of my invention is to provide the casing of a gage, as an odometer or speedometer with a disk having a lamp receiving chamber which is overlaid by an opaque dial, the disk and casing having associated therewith means for supporting the lamp, its socket and connecting piece so that such parts may be readily removed to renew the lamp, the dial having openings for exposing portions of the registering cylinders or number-wheels.

A further object of my invention is to provide a gage, odometer or speedometer with an apertured dial the walls of the dial being upturned, the cylinders or number wheels being below the openings, such gage, odometer or speedometer having within its casing an incandescent lamp so situated that the light rays therefrom will illuminate both

sides of the exposed portions of the cylinders or number wheels, one side of the centers thereof being rendered visible by direct light rays and the other side by reflected light. 60

A further object of my invention is to provide a gage, odometer or speedometer with an internally maintained incandescent electric lamp the incandescent element thereof being located to impact upon an angularly disposed part of the dial and to be directed upon a part of the indicating cylinders or number wheels that is opposite to the lamp. 65

In the accompanying drawings which illustrate a preferred form of my invention, 70 Figure 1 is a front elevation of a speedometer, the glass and the dial being partly broken away to show the lamp and a portion of the disk that is adjacent to the lamp. Fig. 2 is a sectional view, taken substantially 75 on the line 2—2 on Fig. 1, and Fig. 3 is a diagrammatic view.

The odometer or speedometer as to the construction of its casing, the indicating cylinders or number-wheels, the mechanism 80 for actuating the indicating cylinders or number wheels and for setting the same, and of the means for maintaining the glass and the dial may be of the usual and well known construction arranged to provide within the 85 casing space for a disk or plate and a lamp and the parts associated with the lamp to maintain the same in position.

The casing 1 is provided at its rear with an opening 2 of a size to admit of the insertion of a tube 3, the lower or outer end of the tube having a flange to overlie the exterior portion of the casing surrounding the opening. The casing is also provided with interior means for holding in place a plate 90 4 that has formed therein a bowl-shaped depression 5 that has an opening 6 and a flange 7 with exterior threads to engage with interior threads on the tube 3. The plate 4 has therethrough openings for the indicating 100 disks or number wheels 8, the openings being somewhat larger than the sight openings through the dial 9.

The dial 9 is maintained so that its underside will be above the surface of the indicating disks or number wheels, and the longitudinal edges of the dial adjacent to the sight openings are bent at an angle, to provide a light space between the surface of the indicating disks or number wheels and to 110 provide a reflecting surface to direct the rays of light from the lamp upon the surface of

the indicating disks, after the light rays have passed the center of the indicating disks.

The incandescent electric lamp 10, may be 5 a 3-candle power Tungsten electric light of a diameter less than the internal diameter of the opening 3 which is surrounded by the flange of the bowl-shaped depression 5 formed in the plate 4, the lamp or light 10 being maintained by a socket 11 which has a flange to be engaged by a shoulder on the tube 3 and the edge of the flange 7, the tube also being adapted to receive a connector 12. 15 To replace a lamp the connector 12 is first removed from the tube, the tube is then unscrewed to admit of the removal of the socket and the lamp so that a new one can be inserted in the socket.

The device constructed as described locates the lamp within the casing so as to 20 avoid projecting parts and to protect the lamp, the illumination from the lamp being confined to the light chamber between the dial and plate the light rays illuminating the cylinder or number wheels to render the parts thereof immediately opposite the openings visible.

The position of the lamp and the bowl-shaped chamber therefor as well as the tube 30 that receives the socket and connector, when one is used, may be varied to suit the mechanism contained within the casing, and the opening through the casing instead of being as shown may be through the side of the 35 casing, or elsewhere, but always beneath an opaque dial face so that the rays will not be in line with the eyes of the user.

I claim.

1. In an odometer or speedometer having 40 a dial with openings therethrough and indicators maintained opposite the aforesaid openings through the dial, a plate having therethrough openings which register with the openings through the dial the plate being 45 maintained to provide a space between the same and the dial said plate having a depressed portion, and a lamp maintained within the depressed portion of the plate.

2. In a device of the character set forth, 50 a dial having sight openings therethrough, a plate that is spaced apart from and is maintained parallel with the dial said plate

having a depressed portion to one side of its major portion and openings in alinement with the sight openings through the dial, indicators which extend through the openings formed in the plate, and an incandescent electric light maintained within the depressed portion of the plate to be located beneath the dial. 55

3. In a device of the character set forth, an opaque dial or plate having sight openings therethrough, indicators maintained below the sight openings, a plate having therethrough openings which are in alinement 60 with the openings through the dial through which extend a portion of the indicators said plate also having a depressed portion, a lamp associated with the plate and means for maintaining the plate and dial separated 65 to provide a light chamber.

4. In a device of the character set forth, an opaque dial having a sight opening therethrough the opposite sides of the sight opening being bent to be disposed at converging 70 angles above the plane of the dial, a cylindrical indicator maintained so that its surface will be below the plane of the dial, an illuminating means maintained so that direct light rays therefrom will illuminate an 75 exposed portion of the indicator and deflected light rays will illuminate the exposed portion of the indicator on the opposite side of the center of the indicator from that part thereof which is illuminated by the direct 80 light rays.

5. In a device of the character described, a casing, a dial having sight openings therethrough, a plate which is maintained parallel with the dial and is provided with 90 openings which register with the sight openings through the dial said plate also having a depressed bowl-shaped portion with a hollow tubular wall, a member maintained in detachable engagement with the tubular 95 wall, and a socket for an electric lamp associated with the hollow tubular wall of the plate and with its detachable engaging member.

EDWARD S. ABRAHAMS.
